GARBAGE CAN

George W. Rienks and Edward T. Guilford,
Denver, Colo.

Application October 14, 1935, Serial No. 44,855

5 Claims. (Cl. 248—147)

This invention relates to improvements in supports and cover operating means for garbage cans and similar receptacles.

In the disposal of garbage from homes and apartment houses, the garbage is put into cans and the like that are placed adjacent the alley or street where it is collected at regular intervals by collectors employed by the city for this purpose.

10 Since garbage cans contain food of different kinds, they naturally attract flies and, if they are not properly covered, they become regular breeding places for flies, or at least serve as hosts for swarms of them. Uncovered and improperly covered garbage cans also serve as feeding places for cats, dogs and rats, and are unsanitary and disease-breeding.

It is universally recognized that garbage cans must be properly covered, but experience has shown that garbage can covers are short-lived, and they soon become bent, broken or stolen, or the cans capsized and the contents spilled. An inspection of any city will show that the great majority of garbage cans are either entirely uncovered or else improperly covered.

20 Owing to the lack of planning on the part of the builders or owners, there is seldom provided convenient supports for the garbage cans, and as a result, the collector's work is greatly increased and their treatment of the cans is not as considerate as it would be if they were conveniently located.

It is the object of this invention to produce a support for garbage cans, that can be positioned 30 in a gap in the back fence, and which will support a garbage can so that it will be conveniently accessible from the inside of the fence for depositing garbage therein, and which will be equally accessible to the garbage collector for removing the can therefrom while emptying it.

40 Another object is to produce a device of the kind under consideration that shall carry a suitable cover and which shall be provided with means for raising the cover when the can is to be removed, and for lowering it onto the can when the latter is replaced.

Another object of this invention is to produce a cover that shall be provided with an opening, which in turn has a cover for closing it, and which is employed when placing garbage into the can.

45 A further object is to provide means, operable from the outside of the yard and accessible to the garbage collector for raising the cover and for holding it in raised position while the can is being emptied, and which will automatically re-

lease and lower the cover onto the can when the latter is replaced.

A still further object is to provide a support, of the kind pointed out, that shall be so constructed that the parts can be locked whenever desired, so as to prevent removal of the can or contents by persons bent on theft or mischief.

The above and any other objects that may appear as this description proceeds, are attained by means of a construction and an arrangement 10 of parts that will now be described in detail, and for this purpose reference will be had to the accompanying drawings, in which the preferred embodiment has been shown, and in which—

Figure 1 is a side elevation, looking in the 15 direction of arrow 1 in Figure 2;

Figure 2 is a front elevation, looking in the direction of arrow 2 in Figure 1;

Figure 3 is a top plan view of the assembly shown in Figures 1 and 2;

Figure 4 is a view, similar to the one shown in Figure 1, with a small portion broken away, and shows the cover in raised position, and the can partly removed;

Figure 5 is a side elevation, corresponding to that shown in Figure 1, and illustrates a specifically different mechanism for raising and lowering the cover;

Figure 6 is a top plan view of the assembly shown in Figure 5; and

Figure 7 is a transverse section through the 30 cover and the upper end of the can.

In the drawings reference numeral 10 designates the two parallel, spaced side angle iron members of the supporting frame. Secured at 35 their lower ends to the vertical flanges of the angle irons 10 are four corner posts 11 that are also formed from angle iron. The side shown in elevation in Figure 2 will be referred to as the front side, so as to facilitate the description. 40

The two corner posts at the back of the frame are connected by two angle iron members 12 and 13, and by a flat bar 14. The two corner posts at the front of the frame are connected by a flat bar 15. 45

The upper ends of the front and rear corner posts on each side are connected by angle irons 16, and lower down by the angle irons 17. The rear ends of the latter rest on, and are secured to the inwardly extending flange of the angle iron 50 13, and have the front ends of their vertical flanges bent outwardly as indicated by reference numeral 18, and secured to the corner posts. The inwardly extending or horizontal flanges of the angle irons 17 serve as supports for the garbage 55

can 19. Flat bars 20 extend from the angle iron 13 to the bar 15 in the space between the supporting angles 17.

A bar 21 extends between the vertical flanges of the angle irons 10, and has its end secured by brackets or bent ends 22. Two short pieces of angle iron, 23 and 24, are secured to the bar 21. A lever comprising the two bars 25 is fulcrumed on the pivot 26 at the tops of members 23 and 24. The front ends of bars 25 are connected by a pedal 27, and the rear ends carry a transverse bar 28 to the outer ends of which the links 29 are pivoted. Rods 30 have their lower ends pivoted to the lower ends of the links 29, and pass through openings in the guides 31 and the horizontal flanges of the angle irons 16.

A flanged cover 32 is attached to the upper ends of the rods 30 in the manner shown in Figures 1 and 2. Normally, the cover rests on the top of the can, but when sufficient pressure is applied to the pedal 27, the cover is raised to the position shown in Figure 4.

When the cover is elevated to the position shown in Figure 4, and the can moved outwardly a short distance, a latch becomes effective to hold it in this position until released by the movement of the can to normal position. The latch comprises a straight bar 33 that has its lower end pivoted on the bar 34. The upper end of this bar 33 has a notch 35 in which the rod 28 engages when it is elevated to the position shown in Figure 4.

An arm 36 extends rearwardly from the bar 33 near its upper end, and is provided with an upward end 37 that projects between the guide bars 36a to a point above the bottom of the can and is engaged by the latter when in normal position, (Figure 1), and when in this position, the latch is held in inoperative position. When the can is pulled out (Figure 4), the latch member is free to engage the rod 28. After the can has been emptied and is returned to its normal position, the latch is moved into inoperative position, and the cover is then free to move down to its normal position on the can.

A perforated lug 38 is secured to the bar 39 in position for receiving the hasp of a padlock 40 that also encircles one of the levers 25. When the lock is in place, the cover cannot be raised, and the can and cover are thus locked to the support and secured against removal by mischievous boys or thieves.

In Figure 7 a section has been shown through the cover and through the top of the can, and from this it will be seen that besides the usual flange that surrounds the can, the cover has a central opening surrounded by a flange 41. A cover 42 is connected with the cover 32 by a hinge 43, and has a handle 44 by means of which it can be tilted. The garbage is deposited in the can through the opening under cover 42.

In Figures 5 and 6, a modified form of cover operating means has been shown which takes the place of the pedal operated device described above. The modified cover operating device consists of a bail 45 that is pivoted to the lugs 46, which are carried by the angle irons 16a. Short connecting rods or links 47 have their upper ends pivoted to the bail at points 48, and their lower ends pivoted to the rods 30. When the bail is in the position shown in full lines in Figures 5 and 6, the cover is in operative position, but when it is turned to the dotted line position, the cover is also raised to dotted line position.

The lower ends of rods 30 are provided with

heads 49 that are so located with respect to the lugs 31 that they will engage the under sides of the lugs after the bail has been raised from the full line to the dotted line position shown in Figure 5. After the bail has been operated to raise the cover, the parts will remain in raised position until the bail is manually returned.

A perforated lug 38a is fastened to the angle iron 16a, and a padlock 40 can be attached to the lug and surround the bail in the manner shown. 10

The can has a handle 50 by means of which it can be pulled outwardly and returned. In Figure 3, the fence between the lot and the alley has been shown and designated by numeral 51, and it will be seen that the supporting frame occupies 15 a position in a gap in the fence, the pedal being on the outside so that the garbage collector can remove and replace the can without entering into the yard, and the owner can empty the garbage without leaving the yard. 20

The base of the frame is apertured at 52 to permit the frame being anchored by bolts or the like to a concrete foundation. The frame can also be held against unauthorized removal by the use of bolts or the like, inserted through apertures 53 for attachment to the fence. 25

On Hallowe'en and when the house is vacant, the cover can be locked in position, and assurance thus had that the frame, can or cover will not be removed. 30

From the foregoing it will be seen that the support and can which form the subject of this invention, are so constructed that they are convenient for both the owner and garbage collector, and that whenever desirable, the parts can be 35 locked against removal.

Having described the invention, what is claimed as new is:

1. A garbage can support and cover operating means comprising, a vertically extending frame 40 having means for supporting a garbage can, the frame above the support having an opening through which the can may be removed, two rods slidably connected with the frame for vertical movement, the rods being positioned on 45 opposite sides of the frame, a cover for the top of the garbage can, carried by the rods for vertical movement, a bail having its ends pivoted to the frame, and links connecting the rods to the bail whereby when the bail is turned about its pivots, 50 it acts as a lever and raises and lowers the cover, the bail, when the cover is on the can, being positioned to close the opening in the frame.

2. A garbage can support and cover operating means comprising, a vertically extending frame 55 having means for supporting a garbage can, the frame above the support having an opening through which the can may be removed, two rods slidably connected with the frame for vertical movement, the rods being positioned on opposite 60 sides of the frame, a cover for the top of the garbage can, carried by the rods for movement therewith, a bail having its ends pivoted to the frame, and links connecting the rods to the bail, whereby when the bail is turned about its pivots, it acts 65 as a lever and raises and lowers the cover.

3. A device of the character described, comprising a can, a frame inclusive of a support for the can, having an opening for the lateral removal of the can, a cover for the can, rods attached to opposite sides of the cover and slidably mounted on the frame, a foot pedal pivotally mounted on the frame, mechanism connecting the pedal to the rods for converting the movement of the pivoted pedal to sliding movement of the rods, 70 75

whereby the cover is raised, and a gravity actuated catch mounted on the frame, to hold the cover in a raised position, and adapted to be released by movement of the can onto the support.

5. A device of the character described, comprising, a garbage can, a frame open at one side and having a support for the can, a bail pivoted to the frame and normally closing its open side, a cover for the can, removable by upward movement, mechanism for lifting the cover from the can through the intermediary of the bail by upward movement thereof.

10. A device of the character described, comprising, a garbage can, a frame open at one side and having a support for the can, a bail pivoted to the frame and normally closing its open side, a cover for the can, removable by upward movement, mechanism for lifting the cover from the can through the intermediary of the bail by upward movement thereof.

5. A device of the character described, comprising a garbage can, a frame open at one side and having a support for the can, a bail pivoted to the frame and normally closing the open side, a cover for the can, removable by upward movement, mechanism for lifting the cover from the can through the intermediary of the bail by upward movement thereof, and locking means for holding the bail against unauthorized movement, in its normal position on the frame.
